United States Patent Office

Des. 227,391
Patented June 19, 1973

227,391

ROW CROP HARVESTING ATTACHMENT

Allan Keith Lawrence, Ottumwa, Iowa, assignor to
Deere & Company, Moline, Ill.

Filed July 24, 1972, Ser. No. 274,567

Term of patent 14 years

Int. Cl. D15—03

U.S. Cl. D40—1 E

FIG. 1

FIG. 2

FIG. 3

FIG. 1 is a right front perspective view of a three-row harvesting attachment embodying my new design.

FIG. 2 is a right side elevation view thereof.

FIG. 3 is a left side elevation view thereof.

I claim:

The ornamental design for a row crop harvesting attachment, substantially as shown.
